CLAIM

The ornamental design for the rechargeable clip light as shown and described.

DESCRIPTION

FIG. 1 shows a front perspective view of a rechargeable clip light;

FIG. 2 shows a top view of the rechargeable clip light of FIG. 1;

FIG. 3 shows a bottom view of the rechargeable clip light of FIG. 1;

FIG. 4 shows a right side view of the rechargeable clip light of FIG. 1;

FIG. 5 shows a left side view of the rechargeable clip light of FIG. 1;

FIG. 6 shows a rear view of the rechargeable clip light of FIG. 1; and,

FIG. 7 shows a front view of the rechargeable clip light of FIG. 1.

The broken lines in the drawings depict portions of the rechargeable clip light that form no part of the claimed design.
